GASEOUS ELECTRIC DISCHARGE DEVICE

Hans Jancke and Robert Rompe, Berlin, Germany, assignors to General Electric Company, a corporation of New York

Application February 18, 1936, Serial No. 64,557.
Renewed November 12, 1938. In Germany
February 25, 1935

3 Claims. (CL. 176—42)

The present invention relates to gaseous electric discharge devices generally and more particularly the invention relates to such devices comprising a tubular quartz container having a starting gas therein and tellurium electrodes sealed therein similar to that described in co-pending application Serial Number 26,674, filed June 14, 1935, the inventor being Robert Rompe.

The lamp disclosed in the co-pending application referred to above is preferably operated at a container temperature greater than 750° C. and a tellurium vapor pressure greater than 0.1 mm. and the light emitted thereby closely approaches daylight in color. At room temperature the tellurium electrodes are crystalline solids but during operation of the lamp the electrodes are liquid. In changing from the solid to the liquid state the tellurium expands and frequently exerts sufficient force on the electrode chambers to crack or break the latter terminating the useful life of the lamp. Conversely when the lamp is turned off the tellurium changes from a liquid to a solid state and in so doing contracts. Frequently the solidified tellurium does not make contact with the current lead which makes the re-starting of the lamp impossible.

The object of the present invention is to provide a gaseous electric discharge lamp having tellurium electrodes which has a long useful operating life and which is easily restarted. Still further objects and advantages attaching to the device and to its use and operation will be apparent to those skilled in the art from the following particular description.

The invention attains its objects by mounting a resilient, conically shaped receptacle in each of the electrode chambers of the lamp container. The receptacle consists of electrically conducting, high melting point, resilient material and is connected to the current lead sealed into the electrode chamber. A quantity of tellurium is located in said receptacle. The conical shape and the resiliency of the receptacle permits the tellurium to expand and contract freely during the service of the lamp to avoid destructive forces on the walls of the electrode chamber. Further, the unique shape of the electrically conducting receptacle insures a good electrical connection between the current lead and the tellurium electrode when the tellurium is in either the solid or the liquid state so that the lamp is easily started into operation.

In the drawing accompanying and forming part of this specification a lamp embodying the invention is shown, in which

Fig. 1 is a side elevational view of the lamp, and

Fig. 2 is an enlarged, side sectional view of one end of the lamp illustrated in Fig. 1.

Like numbers denote like parts in both the figures.

Referring to the drawing the lamp comprises an elongated tubular quartz container 1 having a starting gas therein, such as argon, neon, xenon, or the like, and having at each end thereof an electrode chamber 2 which is conical in shape and opens into the tubular part of the container 1. Each of the electrode chambers 2 has a tubular member 3 fused thereto and surrounding a rod 4. The rod 4 is the current lead and terminates in the electrode chamber 2.

The receptacle consists of a resilient wire 6, 7 of high melting point material, such as tungsten, one end of which is attached to the inner end 5 of the current lead 4, as by welding, and the part 20 6 of which is wrapped closely around the part of the rod 4 extending along the axis of the conically shaped electrode chamber 2. The wire 6, 7 is coiled in such manner that each turn thereof is contiguous to the turns on either side thereof and the part 7 of the wire 6, 7 is contiguous to the inner surface of the electrode chamber 2. The part 7 of the wire thus forms a resilient body 30 interposed between the tellurium contained therein and the electrode chamber 2.

The inner portion of the electrode lead 4 extends an appreciable distance into the electrode chamber 2 and terminates below the brim of the receptacle formed by the wire 6, 7. Said receptacle is filled to the brim with a body 8 of tellurium (in the drawing the receptacle is shown only half full for the sake of clarity of illustration). The advantages of the conically shaped, electrically conducting, resilient receptacle formed by the wire 6, 7 in the electrode chamber 2 have 35 been mentioned above.

The joint between rod 4 and the tubular member 3 is a ground, gas tight one, when desired, or a fused, graded seal is used between the rod 4 and the electrode chamber 2, when desired. The 40 receptacle is made of sheet metal and has a plurality of slits therein for resiliency, when desired.

While we have shown and described and have pointed out in the annexed claims certain novel features of the invention, it will be understood that various omissions, substitutions and changes in the forms and details of the device illustrated and in its use and operation may be made by those skilled in the art without departing from the broad spirit and scope of the invention.

What we claim as new and desire to secure by Letters Patent of the United States, is:

1. An electric discharge device comprising a sealed vitreous container, a gaseous atmosphere therein, an electrode chamber of vitreous material fused thereto, a current lead sealed into said electrode chamber, a quantity of vaporizable material in said electrode chamber, said material being solid at room temperature and liquid during the operation of said device and a resilient receptacle of electrically conducting material for said vaporizable material, said receptacle being connected to said current lead and being mounted in said electrode chamber, the walls of said receptacle being interposed between said material and said chamber, said receptacle being capable of containing said material in its liquid state and being capable of expanding under the forces generated with increasing temperature in the material in its solid state to dissipate said forces to prevent rupture thereby of said chamber walls during the starting of said lamp.
2. An electric discharge lamp comprising a sealed vitreous container, a gaseous atmosphere therein, an electrode chamber of vitreous material fused thereto, a current lead sealed into said electrode chamber, a quantity of vaporizable material in said electrode chamber, said material being solid at room temperature and liquid during the operation of said lamp and a resilient receptacle of electrically conducting material for said vaporizable material, said electrode chamber being substantially conical in shape, said current lead extending along the axis of said chamber, said receptacle conforming to the shape of said electrode chamber, being connected to said current lead and being mounted in said electrode chamber, the walls of said receptacle being inter-

posed between said material and said chamber, said receptacle being capable of containing said material in its liquid state and being capable of expanding under the forces generated with increasing temperature in the material in its solid state to dissipate said forces to prevent rupture thereby of said chamber walls during the starting of said lamp.

3. An electric discharge lamp comprising a sealed vitreous container, a gaseous atmosphere therein, an electrode chamber of vitreous material fused thereto, a current lead sealed into said electrode chamber, a quantity of vaporizable material in said electrode chamber, said material being solid at room temperature and liquid during the operation of said lamp and a resilient receptacle of electrically conducting material for said vaporizable material, said electrode chamber being substantially conical in shape, said current lead extending along the axis of said chamber, said receptacle consisting of a resilient wire of high melting point material having one end thereof fused to the inner end of said current lead and being wrapped closely around said current lead along the length thereof, the part of said wire out of contact with said lead being coiled in conical shape, the turns thereof being contiguous with each other and with the inner surface of said container and extending beyond the inner end of said current lead, said receptacle being capable of containing said material in its liquid state and being capable of expanding under the forces generated with increasing temperature in the material in its solid state to dissipate said forces to prevent rupture thereby of said chamber walls during the starting of said lamp.

HANS JANCKE.
ROBERT ROMPE.
